CLAIM

The ornamental design for a hair dryer, as shown and described.

DESCRIPTION

FIG. 1 is front perspective view of a first embodiment of the hair dryer showing my new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a front view thereof;

FIG. 7 is a rear view thereof;

FIG. 8 is a right side elevational view of a second embodiment of the hair dryer shown in a folded configuration. The second embodiment differs from the first embodiment only in that it is foldable. The appearance of the second embodiment when in the unfolded position is the same as the first embodiment; and,

FIG. 9 is a left side elevational view of FIG. 8.
